UNITED STATES PATENT OFFICE.

GEORGE WILKINSON, OF PROVIDENCE, RHODE ISLAND, ASSIGNOR TO
GORHAM MANUFACTURING COMPANY, OF SAME PLACE.

DESIGN FOR SPOON AND FORK HANDLES.

Specification forming part of Design No. 9,420, dated August 1, 1876; application filed July 11, 1876.
[Term of Patent 7 years.]

To all whom it may concern:

Be it known that I, GEORGE WILKINSON, of the city and county of Providence and State of Rhode Island, have invented a new and original Design for the Handles of Spoons and Forks in Silver and Plated Wares, of which the following is a specification:

In the accompanying photograph, Figure 1 represents a front view of the design, which consists of a raised border-line, of the form as indicated in the photograph, the said border-line inclosing the main features of the design, consisting of scroll-work, wreaths, leaves, and

branches, surrounding the prominent feature of the design—viz., a female head in cameo form—substantially as shown in the said photograph; Fig. 2 representing the reverse view of the said design.

I claim as my invention—

The design for spoon and fork handles, substantially as herein set forth.

GEORGE WILKINSON.
